UNITED STATES PATENT OFFICE.

ALFRED C. SMITH, OF NEW YORK, N. Y.

DISPLAY-STAND FOR NON-MAGNETIC WATCHES.

SPECIFICATION forming part of Letters Patent No. 378,339, dated February 21, 1888.

Application filed December 17, 1887. Serial No. 253,185. (No model.)

To all whom it may concern:

Be it known that I, ALFRED C. SMITH, a citizen of the United States, residing at New York, in the county of New York and State of New York, have invented certain new and useful Improvements in Display-Stands for Non-Magnetic Watches; and I do hereby declare the following to be a full, clear, and exact description of the invention, such as will enable others skilled in the art to which it appertains to make and use the same.

It is a well-known fact that when ordinary watches having magnetic parts are brought within the field of a magnet said parts become magnetized, and the movement of the watch is either stopped, rendered useless, or seriously affected.

Various kinds of alleged non-magnetic watches are in the market and offered for sale to persons who have not sufficient skill or no convenient means for testing their non-magnetic genuineness.

My invention relates to a novel display-stand for the exhibition of non-magnetic watches or watch-movements; and the improvement consists, essentially, in a display-stand supporting one or more watches or watch-movements and one or more magnets in close proximity to each other, so as to show to the purchaser or other person inspecting the same that the movement of the watch will not be arrested by the action of the magnet or magnets; and it further consists in the construction and combination of parts hereinafter disclosed in the description, drawings, and claims.

In the accompanying drawings, wherein the same reference-letters indicate the same or corresponding parts, Figure 1 represents a front elevation of the preferred form of my display-stand supporting a series of magnets and a watch-movement with its case or cover. Fig. 2 represents an elevation, and Fig. 3 a vertical section, of a modified form of said stand for supporting a single watch and magnet, with said watch and magnet detached therefrom.

The board or tray A of the stand in the several figures of the drawings is of rectangular shape, supported in an upright or slightly-inclined position by a prop, B, and preferably made of wood covered with velvet or other

suitable material. A recess, C, in the tray receives the watch or watch-movement and its cover or case D, and one or more raised supports, E, adapted to fit the interiors of the horseshoe-magnets F, project above the surface of the tray, so as to hold said magnet or magnets radially to the watch or movement, with the poles of the magnets in close proximity thereto.

An ordinary watch or movement having parts of magnetic metal—such as iron or nickel—if placed in the recess C of the stand and within the field of the magnets F will become magnetized thereby, and the magnetized parts will tend to fix themselves in the direction of the magnetic meridian and the correct balance and movement of the suspended parts will be intercepted, thereby rendering the watch useless. In fact such watches are utterly ruined when brought near a dynamo, a magnet, or an electrical wire. Non-magnetic watches will not be thus influenced, but may be safely placed in the recess C of the stand within the field of the magnets, and, being properly wound, will keep accurate time notwithstanding their close proximity to said magnets. A jeweler or watch-manufacturer may thus show his non-magnetic watches to purchasers, who may readily see or test their genuine character.

The stand shown in Fig. 1 has four horseshoe-magnets held upon the raised supports E and arranged diagonally upon the board and radially around the watch or movement holding recess, with their poles located oppositely to each other, and is also provided with raised tablets upon the four sides thereof and between the said horseshoe-magnets, the tablets being respectively marked "non-magnetic watches," "adjusted to temperature," "isochronism and position," "uninfluenced by magnetism."

The design or configuration of the stand may be varied to suit the fancy of the dealer, and the raised supports E may be adapted to fit the exterior, instead of the interior, of the horseshoe-magnets; or any number of watches and magnets may be employed, and they may be held or supported in various ways upon the board without departing from my invention.

Having thus fully described my invention,

its operation, and use or purpose, what I claim as new is—

1. In a display-stand, the combination of one or more magnets supported upon said stand, 5 and a watch or watch-movement also supported upon said stand and arranged in proximity to said magnet or magnets for the purpose of attracting attention to the magnetic character of said watch or watch-movements, substantially as described.

2. A display-stand for exhibiting the non-magnetic character of watches, consisting of a tray or board, A, having a central recess, C, for receiving a watch or watch-movement, and 15 a series of radial supports, E, for holding horseshoe-magnets, and arranged to encircle said central recess, substantially as described.

3. A display-stand for exhibiting the non-magnetic character of watches, consisting of a tray or board, A, having a central watch-recess, C, radial magnet-supports E, surrounding said watch-recess, and a series of tablets located between said magnet-supports, and upon which are inscribed the characteristics of the watches exhibited, substantially as described. 20 25

In testimony whereof I affix my signature in presence of two witnesses.

ALFRED C. SMITH.
